KNITTING MACHINE

Arthur Shortland, Leicester, England, assignor to
 Mellor Bromley and Co. Limited, Leicester, England

Application March 22, 1943, Serial No. 480,073
 In Great Britain December 31, 1941

3 Claims. (Cl. 66—110)

1

This invention comprises improvements in rotary or straight bar knitting machines, having a line of needles and a line of sinkers movable one after the other between the needles. In such machines (of which the Cotton's Patent is the modern example) as at present constructed two kinds of sinkers are employed, jack sinkers that are projected, one in every second needle space, through the medium of pivoted jacks engaged by a slurcock which travels along the machine and engages the jacks one after another, and dividers that are subsequently advanced in unison, one in every other needle space, by a catch bar which at a still later stage serves to retract all the sinkers.

According to the present invention there is provided, in a rotary or straight bar knitting machine, sinker advancing mechanism comprising a helical cam arranged with its longitudinal axis lengthwise of the line of the needles, which cam is rotatable about said axis to advance the sinkers serially. It will be appreciated that as the cam rotates, successive portions in the length thereof operate directly or indirectly on successive sinkers to advance the sinkers seriatim, and it is preferred that the cam shall be located at the back of the sinker head with its axis of rotation horizontal. It may operate directly on parts (e. g. the rear ends) of the sinkers, which are preferably reinforced or thickened to provide adequate wearing surface, or a suitable motion-transmitting member may be interposed between the cam and each沉器 to be projected thereby. For example, said members may be rocking jacks (similar to the conventional jacks in Cotton's Patent machines) or thrust blades or sliding jacks.

The cam, the axial length of which is preferably at least as great as that of the line of sinkers, preferably extends through less than one complete turn, so that in one position of rotation it is entirely inoperative. During this inoperative phase other knitting motions may take place, for example, the retraction of the sinkers by a catch bar. It is necessary, however, for the serial projection of the sinkers to take place first in one direction along the line starting at one end thereof and then, for the next course, in the reverse direction from the other end. In order to meet this desideratum, the direction of movement of the cam is reversed at each end of the "draw."

The foregoing and other features of the invention set out in the appended claims are incorporated in the constructions which will now be de-

2

scribed in detail with reference to the accompanying drawings, in which

Figure 1 is a diagram showing the operation of a helical cam according to this invention on sinkers or sinker-moving instruments;

Figures 2, 3 and 4 are diagrams respectively indicating the facts that said cam may either operate direct on the sinkers, or on the jacks, or on thrust members or sliders interposed between it and the sinkers;

Figure 5 is a cross section showing the relevant parts of a Cotton's Patent or other straight bar or rotary knitting machine incorporating the invention;

Figure 6 is an elevation, and Figure 7 a cross section through one construction of cam;

Figure 8 is a perspective view of another cam, and Figure 9 is a detail thereof;

Figures 10 and 11 show another construction 20 of cam; and

Figure 12 shows a still further construction.

Referring primarily to Fig. 1 on a drum 10 supported by a shaft 11 for movement of at least partial rotation about the shaft axis, there is a helical cam 12 which extends for less than one complete turn, and it will be appreciated that as this cam is angularly displaced about the axis of the shaft it causes instruments 13 with which it engages to be projected serially. As shown in Fig. 2 the said cam may engage directly with the sinkers 14, said sinkers conveniently having their rear ends reinforced as at 15. Alternatively as shown in Fig. 3 it may engage with jacks 16 interposed between it and jack sinkers 14, or in the third alternative shown in Fig. 5 the cam may engage with sliders or thrust blades 17 interposed between it and the sinkers 14, the said members 17 being slidable in a bed 18. It will therefore be understood that the members 13 in Fig. 1 may be taken as representing either the sinkers 14 of Fig. 2 or the jacks 16 of Fig. 3 or the blades 17 of Fig. 4.

As seen in a section normal to the axis of oscillation it is necessary for that flank of the cam which first meets the sinkers 14 or the motion-transmitting members (e. g. the flank 12a in Fig. 3) to be suitably shaped or inclined to impart the desired movement to the sinkers. This shape is desirably such that the sinker movements resemble as closely as possible those imparted by the usual slurcock. In the case of a cam which reverses its rotation both flanks should be shaped in this manner as are the flanks 12a and 12b in Fig. 3. The cam may also have a concentric portion or dwell 12c at its crest whereby a plurality

of sinkers is held in position of maximum advance for a short period.

Turning now to Fig. 5, this illustrates the application of the invention to a rotary or straight bar knitting machine, primarily a Cotton's Patent machine, and in this figure only those parts which are essential to an understanding of the invention are shown, since the remaining parts are well understood in the art and need no illustration or description herein. The sinkers 14 are mounted in a sinker head 19 which is supported on a head rail 20 extending between the cross frames 21, said frames being further connected by template rail 22, front rail 23 and back rail 24. The head rail 20 further carries the bed 18 in which the thrust blades 17 are supported, and also carries bearings 25 on which the helical cam 12 is mounted for oscillation about the axis 11 so that as it oscillates the "jack" sinkers 14 are projected serially first from one end of the division and then from the other. These sinker motions are similar to those imparted by the usual slurcock during the draw. The dividing sinkers are projected towards the needles 51 in unison by the catch bar 26 and all the sinkers are retracted in unison by said catch bar, these catch bar movements occurring while the helical cam is inoperative.

The mechanism for oscillating the helical cam 12 about its axis 11 is here shown by way of example as consisting of a draw lever 27 pivoted at 28 and having a truck 29 engaging a cam track 30 formed on a cam 31 which is mounted on the cam shaft 32 to rotate at the appropriate speed. The free end of this draw lever is connected to an upright rack 33 guided at 34 and engaging a pinion 35 associated with cam 12 so that as the draw lever 27 is oscillated the cam 12 is oscillated also. The cam 12 may have its axis of rotation adjustable laterally for adjustment of stitch quality, and the bearings 25 may be constructed to provide this adjustment, one adjustment means being diagrammatically indicated at 52.

In a multi-section machine, sinker-advancing mechanism according to this invention will be provided for each section.

The cam 12, or each of them, may be formed as a serpentine rib on the periphery of a drum or cylinder or may be formed as a helical member supported from a shaft by radiating arms. In either case the cam may be solid throughout its length or may be built up from a plurality of cam-elements located one after another in serpentine form. Such elements are preferably interchangeable. In one construction (Figs. 6 and 7) incorporating a drum or cylinder 10, the latter is provided in its periphery with spaced annular grooves 39 (so that between successive grooves there are annular "lands" 40); each groove 39 receives a key portion 112' formed on the back of a cam element 112a which extends obliquely to the length of the key portion so as to overlie the adjacent land or lands 40 and to line up with a like element, having its key 112' in the next groove 39, whereby a succession of such elements are disposed in the required helical formation. The elements 112a may be secured in position by screws, e. g. in the case of a hollow drum 10 a screw 41 may extend outwards from the interior thereof into each element, there being a hole 42 through the peripheral wall of the drum 10 diametrically opposite the screw 41 to afford access to the screw head. Alternatively, cam elements may be located in or on a helical groove or other track, which may be provided on the periphery of a cylinder or on a frame

or member itself of helical form and supported from a shaft by radial arms or their equivalent. In one construction, Figs. 8 and 9, a cylindrical drum 10 has a helical groove 43 cut in its periphery, said groove being of dove-tailed or undercut form in section. Plate-like cam elements 112b are slid into this groove 43 from one end thereof, said elements being arranged side by side and being retained by an end plate or other closure 44 for one end of the groove 43. A like arrangement may be employed when the groove 43 is formed in a helical member 45 (Figs. 10 and 11), which may be die-cast. In a modification, one longitudinal edge or boundary of the groove 43 in a helical member aforesaid may be constituted by a detachable boundary strip 46 (which may or may not be undercut) serving to clamp the elements 112b against the boundary of the groove.

It is desirable to provide the radial arms 47 supporting a frame or helical member 45 aforesaid with means for adjusting the radius of the groove 43, so that the cam elements 112b may be set to operate correctly. For this purpose each arm 47 may receive an eccentric bush 48 through which the shaft 11 extends, which bush 48 is rotatably adjustable. The said bush may be tapered externally and split as at 50, to permit it to be locked in the desired position of rotational adjustment within the arm, by a lock nut 49 at one end of it which nut pulls the arm up on to the taper.

In a further construction illustrated in Fig. 12 the cam 12 is built up from a plurality of lobe-like cam elements 112c threaded on the shaft 11 and positioned in the appropriate spiral formation by the engagement of a projecting pin 36 in each element with the hole 37 in the next element, the spacing of the pin 36 and hole 37 in each element being such as to give the desired pitch to the successive elements. The helical stack of elements 112c is preferably clamped by screw means such as the nut 38.

I claim:

1. In a knitting machine having a line of jack and dividing sinkers, and a catch bar for advancing the dividers and retracting all the sinkers; a helical cam mounted adjacent the sinker line for projecting the jack sinkers serially, which cam is of a length at least equal to that of the sinker line, extends through less than one complete turn whereby it is provided with an ineffective portion and comprises a cam drum provided with a series of circumferential grooves and a series of cam elements disposed side by side in said groove in helical form; and means for circumferentially moving said cam as a whole about its longitudinal axis, first in one direction to project the jack sinkers serially from one end of the line and then to become inoperative, and then in the reverse direction to project the jack sinkers serially from the other end of the line and to become inoperative again, whereby the catch bar subsequent to the advance of the sinkers may retract all the sinkers during each inoperative phase of the cam.

2. In a knitting machine having a line of jack and dividing sinkers, and a catch bar for advancing the dividers and retracting all the sinkers; a helical cam mounted adjacent the sinker line for projecting the jack sinkers serially, which cam is of a length at least equal to that of the sinker line, and extends through less than one complete turn whereby it is provided with an ineffective portion, which cam comprises a shaft, cam elements threaded on said shaft in

spiral form, and interengaging means on successive elements for positioning them in that form; and means for circumferentially moving said cam as a whole about its longitudinal axis, first in one direction to project the jack sinkers serially from one end of the line and then to become inoperative, and then in the reverse direction to project the jack sinkers serially from the other end of the line and to become inoperative again, whereby the catch bar subsequent to the advance of the sinkers may retract all the sinkers during each inoperative phase of the cam.

3. In a knitting machine having a line of jack and dividing sinkers, and a catch bar for advancing the dividers and retracting all the sinkers; a helical cam mounted adjacent the sinker line for projecting the jack sinkers serially, which cam is of a length at least equal to that of the sinker line, extends through less than one complete turn whereby it is provided with an ineffective portion, and is provided with means for adjusting the radius of parts thereof; and means for circumferentially moving said cam as a whole about its longitudinal axis, first in one 25

direction to project the jack sinkers serially from one end of the line and then to become inoperative, and then in the reverse direction to project the jack sinkers serially from the other end of the line and to become inoperative again, whereby the catch bar subsequent to the advance of the sinkers may retract all the sinkers during each inoperative phase of the cam.

ARTHUR SHORTLAND.
